Attorney.

UNITED STATES PATENT OFFICE.

HEINRICH REUTER, OF HANOVER, HANOVER, GERMANY.

COMBINED FLUTING AND SMOOTHING IRON.

SPECIFICATION forming part of Letters Patent No. 336,435, dated February 16, 1886.

Application filed July 2, 1885. Serial No. 170,461. (No model.)

To all whom it may concern:

Be it known that I, HEINRICH REUTER, a citizen of the Empire of Germany, residing at Hanover, in the Province of Hanover, Germany, have invented certain new and useful Improvements in a Combined Fluting and Smoothing Iron; and I do hereby declare the following to be a full, clear, and exact description of the invention, such as will enable others skilled in the art to which it appertains to make and use the same.

My invention relates to improvements in that class of combined fluting and smoothing irons which can be alternately used for fluting any material, or as an ordinary smoothing or flat iron; and the object is to produce an iron of such kind that is very simple in its construction, easily interchangeable, not liable to get out of order, and that can be produced at a very moderate cost, so as to be within the reach of every one.

The invention consists in the construction of certain parts and arrangement of details, as will be more fully described hereinafter, and more definitely pointed out in the claim, reference being had to the accompanying drawings and the letters of reference marked thereon.

Like letters indicate similar parts in the different figures of the drawings, in which—

Figure 1 represents a side elevation of my improved fluting and smoothing iron. Fig. 2 is an end elevation of the same. Fig. 3 is a longitudinal section of the same on line *x* *x*. Fig. 4 is a transverse section of the same on line *y* *y*. Fig. 5 is a plan or top view; Fig. 6, a detail view of one of the detachable fluting-plates.

In the drawings, *A* is the main body or lower part of the iron, made of any desired size and shape, and is made smooth on its lower face, and has an open end that is closed by a removable plate or door, *a*, which is held in place by the lugs *a'*. Through the open end a heating-iron or steel plug, *B*, is inserted to heat the iron, and when it is desired to use it said plug is heated to a red heat. The upper side of the body *A* is formed of a detachable

plate, *c*, held in place by the dovetailed sides and lugs *c'*, cast on the body *A*, forming grooves, 50 and by the plate or door *a*. The upper face of this plate is corrugated, so as to form the flutings. The body *A* is provided with a lug, *a''*, to which the upper part, *D*, of the iron is pivoted. The lower face of this part *D* is 55 formed of a removable plate, *d*, also corrugated, and the corrugations thereof correspond with those on plate *c*. This plate *d* is retained in its position by its dovetailed sides, forming grooves, and a thumb-screw, *e*, which presses 60 against the back of said plate and prevents it from slipping out of place. On each side of the part *D*, near its rear end, are arranged the lugs *f*, which depend downward over the sides of the base *A*, and through said lugs pass the 65 set-screws *g g*, which secure the part *D* in place when screwed tightly against the sides of the base, as shown in Fig. 2. The handle *C* is cast with the part *D* in the usual manner.

When it is desired to use the iron as an ordinary flat or smoothing iron, the plug *B*, being properly heated, is inserted through the opening in the base, which is then closed by the door *a*, when the iron will be properly heated by the plug *B* and will be ready for use.

When it is desired to flute any material, the set-screws *g g* are first loosened, the part *D* with its corrugated face-plate is raised on its pivot, the material to be fluted is placed between the upper and lower corrugated plates, 80 *c* and *d*, and when the material has been retained between them a short time it will be found to be properly fluted, and can be moved to the adjoining section to be fluted until completed.

It will be seen that during ordinary flat-ironing, when the face of the body *A* is used, the plates *c* and *d* can be taken out, if desired. In case they become worn out or broken they can be easily replaced by new ones. The use of 90 the plug in its heated state obviates the necessity of placing the iron on a stove or furnace. It can be produced at a very moderate expense, and is not liable to get out of order.

I am aware that fluting-plates made removable from a smoothing-iron, and also that heat-

ing-cores for heating irons of this kind, are broadly not new, and disclaim such as of my invention; but,

Having thus described my invention, what 5 I claim is—

The fluting and smoothing iron herein described, consisting of the base A, the plug B, and part D, hinged to said base A, and the corrugated removable plates c and d, having dove- 10 tailed sides that engage corresponding grooves

in base A and part D, and are secured in place by the door a and set-screw e, all constructed and arranged substantially as shown and specified.

In testimony whereof I hereto affix my signature in presence of two witnesses.

HEINRICH REUTER.
